PRESSURIZED CONTAINERS AND AUXILIARY ADAPTER-ACTUATORS THEREFOR

Harold F. Biewald, 32 Atlantic Ave. E., Oceanside, N.Y.

Filed June 27, 1958, Ser. No. 744,963

5 Claims. (Cl. 141—360)

This invention relates to improvements in pressurized containers for semi-automatically dispensing paste-like compositions, such as tooth paste, or compositions of foam-like consistency, such as aerated shaving cream.

Containers for housing paste-like compositions under pressure, and having a valve-controlled nipple through which the paste may be semi-automatically dispensed, under pressure, when the valve is opened, are well known. In manipulating these devices, it is customary to grasp the container in one hand, while the pressurized paste is discharged, through the nipple, into the other hand, or is deposited upon some tool or article held in the other hand. Moreover before dispensing the pressurized contents from the container, it is customary to shake the container to agitate its contents.

One object of this invention is an improved valve-controlled, pressurized, container, whose contents may be deposited directly, either into the actuating hand, or upon the tool which actuates the control valve.

Another object is an auxiliary device having a dispensing orifice, which device can be detachably attached to the valve-controlled discharged nipple of a pressurized container, in such manner, that when either the hand, or a tool, is brought into actuating-registry with the valve-manipulating mechanism of the auxiliary device, the said hand, or tool is also brought into registry with the dispensing orifice of said auxiliary device, to receive the paste, or other composition, discharged from the pressurized container through the dispensing orifice of the auxiliary device.

Another object is an improved pressurized container which dispenses its contents equally well either in a horizontal, or a vertical, position.

Another object is to effect agitation of the contents of the pressurized container while said container is mounted in fixed position.

Other objects will appear from the detailed description, which follows.

In the drawing, consisting of four sheets of fifteen figures, numbered Figs. 1 to 15, both inclusive:

Fig. 1 is a side elevation of one embodiment of my invention, as applied to a holder-mounted, hand-actuated, semi-automatic, pressurized, dispensing-apparatus.

Fig. 2 is a cross sectional view of the detachable adapter of Fig. 1.

Fig. 3 is a cross sectional view of the adapter of Fig. 2, taken along the line 3—3 of Fig. 2, looking in the direction of the arrows.

Fig. 4 is a plan view of the device of Fig. 3, but inverted.

Fig. 5 is a cross sectional view of one form of interchangeable actuator, which may be used in conjunction with the detachable adapter of Figs. 2 to 4.

Fig. 6 is a front view of the actuator of Fig. 5, looking from the left of Fig. 5, in the direction of the arrows.

Fig. 7 is a cross sectional view of another interchange-

2

able actuator which may be used in conjunction with the detachable adapter of Figs. 2 to 4.

Fig. 8 is a front view of the actuator of Fig. 7, looking from the left of Fig. 7, in the direction of the arrows.

Fig. 9 is a cross sectional view of the actuator of Fig. 7, correlated with the adapter of Fig. 2, and ready to be mounted upon a pressurized container for the dispensing of tooth paste.

10 Figs. 10 and 11, are cross sectional, and front, views, respectively, of the container-holder of Fig. 1.

Fig. 12 is a side elevation of another embodiment of my improved pressurized container, as applied to a tool-actuated, semi-automatic, pressurized, tooth paste dispensing apparatus, cradled in a cradle-type holder.

Fig. 13 is a side elevation, partly in section, and partially broken away, of the dispensing apparatus of Fig. 12, but removed from the cradle holder.

Fig. 14 is a front elevation of the dispensing apparatus 20 of Fig. 13, looking from the right of that figure; and

Fig. 15 is an enlarged cross sectional view of a fragment of the detachable-attachable actuator and valve mechanism of the dispensing apparatus of Fig. 13.

The pressurized container 20 (Fig. 1), may be filled 25 with any suitable paste-like composition, such as shaving cream in aerated form. The conventional container 20 is generally cylindrical.

To effect agitation of the shaving cream, the container 20 is mounted in an upside-down position, between the resilient clamping jaws of the upper, and lower, clamping members, 21 and 22, which are mounted upon a plate 36 (Fig. 10), supported upon the hollow stem of a T-shaped bracket 23 (see Fig. 10). The bracket 23 is mounted to rotate upon a wall plate 24 (Figs. 1 30 and 10), to effect agitation of the container-contents, by rotating the plate 36 which carries the clamping members 21 and 22 the clamping jaws whereof grip the body of the container 20 (Fig. 1). The means for effecting rotation of the bracket 23, are best shown in Fig. 10. A stud 25 is formed integral with the winged plate 30.

The stud 25 passes through a central opening formed in the base flange 29 which is integral with the hollow stem of the bracket 23 (Fig. 10). A coiled spring 28 is mounted upon the stud 25, between the face of the flange 29 and a washer 26 which presses against the end of the coiled spring 28 under control of a lock nut 27 threadably mounted upon the threaded free end of the stud 25. By adjusting the lock nut 27 along the stud 25, the washer 26 varies the tension in the spring 28 to regulate the pressure applied between the abutting

45 faces of the flange 29 and of the winged plate 30. The winged plate 30 is seated in a recess 31 formed in the back wall of the wall plate 24, but only the hub of the winged plate 30 passes through the wall plate 24 from back to front, the wings of said winged plate 30 being seated in the recess 31, and terminating substantially flush with the back face of wall plate 24, or 50 being contained within the face of said wall plate 24 (Fig. 10).

55 Lugs 32 and 33 formed integral with the rear face of the flange 29 protrude rearwardly from said flange, and register in similarly sized cavities formed in the abutting face of the winged plate 30, to index the flange 29 and its bracket 23 at the end of each revolution thereof upon the winged plate 30. The lugs 32 and 33, and their cavities, are of different sizes, and are eccentrically spaced, to insure a complete (360 degree) revolution of the bracket 23, and the return of the container to its upside-down position as each revolution of the bracket 23 is completed. Thus the operator may spin the container 20 once or twice, until the lugs click in the cavities, and

60 relock the container upside-down.

When the container 20 is rotated, the lugs 32 and 33 ride over the face of the hub of the winged plate 30, against increased tension of the coiled spring 28, and when the lugs 32 and 33 return into position of registry with their respective cavities in the abutting face of the hub of the winged plate 30, the coiled spring pushes the flange 29 into contact with the hub of winged plate 30 and reseats the lugs 32 and 33 in their associated cavities in the hub of the winged plate 30. As the lugs 32 and 33 are eccentrically spaced, they cannot register with the wrong cavity in the plate 30.

The clamping jaws of the clamping members 21 and 22, are provided with oppositely disposed, spaced, fingers 34, 34 (Fig. 10), which enter the opposite ends of the tubular bushings 34a, 34a which grip the container 20 (Fig. 1). The clamping members 21 and 22 may be secured to the plate 36 in any preferred manner, as by spot welding, riveting, or otherwise.

If the wall plate 24 is composed of a ceramic, or of a plastic, material, the plate 24 may be bonded to the wall, or other support 35 (Figs. 1 and 10), by means of a suitable bonding agent which is normally non-tacky, but which becomes tacky when moistened with water, or other solvent, and which, while in a tacky condition, will bond with glass, tile, wood, plastic, metal, or the like. Such bonding agents are well known, and are readily available upon the open market.

One control valve mechanism for a pressurized container 20, is shown in Fig. 13. The neck 40 (Fig. 1) of the container 20 is suitably sealed by a cap 41 (Fig. 15). The cap 41 is provided with a central opening wherein a nipple 42 is slidably mounted. The nipple 42 has an enlarged outer end which projects out of the container 20, and a reduced inner end which is an integral extension of the head of a piston 45. Piston 45 is telescopically mounted to slide in a cylinder 46 positioned inside the container 20. A series of ports 43 (Fig. 15), extend through the wall of the nipple 42. The ports 43 are located in the reduced inner end of the nipple and are normally enclosed and sealed by a rubber washer 44. When pressure is applied to the outer end of nipple 42, its reduced inner end projects through the rubber washer 44 (as shown in broken lines, Fig. 15), to uncover the ports 43 and thus establish a restricted passageway for the flow of the pressurized fluid composition housed in the container 20, from said container 20, through the ports 43, into the nipple 42. Since the reduced end of the nipple 42 is formed integral with the head end of the piston 45, the sliding movement of the nipple forces the piston 45 into the cylinder 46 against the opposition of the spring follower 47 which is positioned between the inner end of said piston 45 and the opposed end wall 48 of the cylinder 46. Thus telescopic pressure applied to the outer end of nipple 42, slides piston 45 along the cylinder 46 towards its end wall 48, against increased pressure of coiled spring 47, and when said telescopic pressure is removed, the spring 47 forces the piston 45 to slide in the opposite direction until the rubber washer 44 encloses the ports 43 in the nipple 42. The outer end 49 of the cylinder 46 is enlarged to effect a sealing fit in the throat of the cap 41. The inner end of the cylinder 46 is reduced to form a nipple 50 which is overlapped by, and sealed within, the mouth 51 of the plastic tube 52 (Figs. 15 and 13).

The piston 45 is not a true cylinder. Diametrically opposite segments of said cylindrical piston have been removed, so that said piston only engages some portions of the wall of the cylinder 46 but is spaced away from other portions of the cylinder wall, the curved wall of the cylinder and the non-circular portions of the wall of the piston, in conjunction, defining passageways, said passageways extending co-axially relative to the cylinder 46 and the piston 45 to establish communication between the chamber defined by the container 20, and the nipple 42, under control of the ports 43, by way of the plastic

tube 52, piston-cylinder passageways, ports 43, to the interior of the nipple 42.

As best shown in Fig. 13, the plastic tube 52 is bent to offset the tube 52 towards the wall of the container 20, and is rebent at 53 so that the tube 52 extends along the inner wall of the container 20, and terminates at 54 in spaced proximity to the convex bottom wall 55 of the container 20.

An actuator assembly unit 57 is demountably mountable upon the neck 40 (Fig. 1) of the container 20. The unit 57 includes a bell-mouthed adapter 56 shaped and sized to form a cap which engages the neck 40 of the container 20 with a tight fit. The unit 57 also includes a dispensing head 58 which forms an integral extension of the adapter 56. The head 58 is provided with a duct or passageway 66 which extends through the dispensing head 58, through the valve-actuator 59, to the elbow 67 which is enlarged to receive the outer end of the nipple 42 with a sealing fit. The elbow 67 is stepped to form a shoulder (Fig. 15) which limits the depth of penetration of the nipple 42 in the elbow 67 to prevent closing of the duct 66 in the bend of the elbow.

The valve-actuator 59 is resiliently hinged at 60, upon the lip of the adapter 56, so that the actuator 59 may swing inwardly into the mouth 61 of the adapter 56 when any pressure is applied to the actuator 59. The actuator 59 is recessed at 62 to receive the head of a tooth brush 63, and the dispensing head 58 is shaped somewhat in the form of an inverted letter U, so that, when the bristles 64 of the tooth brush 63 are positioned beneath the dispensing orifice 65 of the dispensing head 58 of the actuator assembly unit 57, the head of the tooth brush will be in position to register with the recess 62 in the actuator 59 to actuate the control-valve, and deposit a ribbon-like stream of tooth paste upon the bristles 64, by way of the ports 43 (now open), nipple 42, elbow ducts 67, 66 and dispensing orifice 65.

The moment that the tooth brush 63 is withdrawn from the recess 62, the valve-actuator 59 swings back into normal position and draws the nipple 42 with it to seal off the ports 43 within the washer 44. The coiled spring 47 restores the piston 45 to normal position, and the control-valve is shut.

For efficient tooth brush operation, the pressurized container 20 is cradled in a cradle-shaped bracket 68 (Fig. 12), which bracket is suitably supported upon the wall or other support 35. By this arrangement, the tooth brush may be used to actuate the control valve of the dispensing apparatus, and to receive the deposit of the tooth paste so dispensed, all by one-hand operation of the tooth brush itself, leaving the other hand entirely free.

By offsetting the tube 52 along the inside wall of the container 20, and extending the tube to a point in close proximity to the convex bottom 55, the contents of the container 20 may be more completely exhausted from the container in its cradled position (Fig. 12). The cradle bracket 68, offset tube 52, and convex bottom 55, in conjunction, thus cooperate to effect the efficient operation of the dispensing apparatus to the point of maximum exhaustion of the contents of the pressurized container, before dispensing pressure is broken at the mouth 54 of the tube 52.

For dispensing shaving cream the arrangement shown in Fig. 1, has proved very satisfactory. The pressurized container 20 is provided with a hook-shaped actuator 70, and the container is secured in an upside down position between the clamping jaws of the upper, and lower, clamping members, 21 and 22, carried by the plate 36 of the bracket 23, supported as by the wall plate 24. The actuator 70 normally assumes a position, substantially as shown in full lines in Fig. 1, but when the hand is inserted, palm upwards, in the bow-shaped opening of the actuator 70, and the actuator is swung by the movement of the hand in the direction of the arrow (Fig. 1), into the position indicated in broken lines in said figure, the nipple

42a is displaced sideways, thus opening the control valve and discharging the shaving cream through the dispensing orifice 65a (Figs. 1 and 5), into the palm of the hand. The actuator 70 is used in association with the adapter 71 (Figs. 1 to 4). The adapter 71 resembles an inverted bell-shaped attachment whose inverted skirt or flange defines an annular collar 72 (Figs. 2 and 3), sized to fit around the neck 40 of container 20 with a tight fit (Fig. 1).

The actuator 70 is mounted in the adapter 71, in such manner, that the actuator is rockable in the adapter to actuate the control-valve to dispense the contents of the pressurized container 20, as desired. The actuator 70, and the adapter 71, are preferably molded pieces, and to reduce the cost of manufacture, these pieces may be molded out of plastic materials, which give good results. The pieces may also be made of metal, or other materials, if desired.

Merging with the collar 72 of the adapter 71, is a crown 73 (Figs. 2 and 3), and said crown is further extended to form a socket or holder, having an end wall 74, two side walls 75 and 76 merging with said end wall 74, and a slotted bottom wall 77 (Fig. 4); said end wall, side walls, and slotted bottom wall in conjunction, thus defining said socket or holder for containing the head 78 of actuator 70.

The bottom wall 77 of the adapter 71, and the bottom wall of the head 78 of the actuator 70, are interfitted by means of bevelled tongues, and reversely bevelled grooves, to define a fulcrum or bearing whereon the head 78 is rockably supported in or by the socket or holder, the side walls 75 and 76 of said socket also serving to maintain said head 78 in correct alignment and thus maintain said fulcrum connection. The bottom wall 77 of the adapter 71 is subdivided into two outer tongues 79, 79 and a central tongue 80, and these three tongues are correlated with three grooves or guideways 81, 81 and a central groove 82 formed in the lower wall 83 of the head 78. The tongues 79, 79 and 80 are wedge-shaped and taper downwardly and outwardly from the end wall 74, along their respective side walls 75 and 76, to a thin edge at the entrance to the socket or holder. The three grooves or guideways 81, 81 and 82, are bevelled to receive and accommodate said wedge-shaped tongues 79, 79 and 80; and the slots or openings 85, 85 formed between each of the tongues 79, and the central tongue 80, are sized to receive and accommodate the tongues 86, which are formed between each of the grooves 81 and the central groove 82 (Fig. 6); said thus interfitted and correlated head 78 and socket therefor, constituting an attachable and detachable actuator 70, rockably supported upon, or within, the socket element of the adapter 71 (see Fig. 1). The central orifice 65a in the throated passage or socket 84 registers with the nipple 42a (Fig. 1), and connects at its lower end with the central groove or guideway 82 (Fig. 6), to provide a dispensing outlet for the nipple 42a. The nipple 42a fits the throated passage or socket 84 with a tight fit to interlock the head 78 in the adapter 71. The nipple 42a is sufficiently resilient to flex when the head 78 of the actuator 70 is rocked in the adapter 71 (Fig. 1), from the position in bold lines to the position shown in broken lines in said figure. When the actuator is in the position shown in bold lines, the central tongue 80 (Figs. 3 and 4) closes off the orifice 65a (Fig. 1); but when the actuator 70 is rocked into the position shown in broken lines in Fig. 1, the central tongue 80 uncovers the orifice 65a, and said orifice is now open and free to dispense paste, or shaving cream, as it is discharged through the nipple 42a from the pressurized container 20. The actuator 70 is well suited for use in conjunction with a pressurized container for dispensing shaving cream into the palm of the hand, see Fig. 1.

The adapter 71, however, may also be attached to the collar-flange or neck 40 of a tooth paste dispensing container (Fig. 13), in which case, the actuator 70 is re-

placed by the tooth-brush-actuated actuator 90 (Fig. 7), which is interchangeable with the actuator 70 of Figs. 1, 5 and 6. The actuator 90 includes a head 78b the lower wall whereof is formed with grooves or guideways 81b, 81b and 82b, which, when they are correlated with the tongues 79, 79 and 80 of the adapter 71, form a rocking connection for the actuator 90. Nipple 42a of the container 20 engages in the throated passage or socket 84b with a sliding fit, and is extended through the bottom wall 83b of the head 78b by the orifice 65b. The actuator 90 is designed to be operated by the pressure exerted through the head of a tooth brush. Actuator 90 is accordingly formed with a tooth brush holder formed by the flaring side walls 91, 92 and the bottom wall 93, said side, and said bottom, walls, in conjunction, defining a trough-like structure, sized to receive the head of a tooth brush, with the bristles facing upwardly towards the orifice 65b, so that, when the tooth brush is placed in the trough 94 with slight pressure, the actuator 90 will carry the nipple (42a, Fig. 1), off-normal, and open the control-valve of the container 20, while simultaneously uncovering the orifice 65b, to provide a dispensing outlet, through which outlet a ribbon of paste may be deposited upon the bristles of the tooth brush. When the tooth brush is removed from the trough 94, the control-valve closes, and the tongue 80 of the adapter 71 moves across the orifice 65b to close off said orifice.

Thus the common adapter 71 may be used in conjunction with either the actuator 70, or the actuator 90, dependent upon the nature of the contents of the pressurized container. The container-holder (Figs. 10 and 11), is equally adapted for use either with a container of shaving cream, or of tooth paste, as desired.

What is claimed is:

1. In a dispensing attachment for a pressurized, valve-controlled container which dispenses paste through a valve-controlling extrusion-nipple and in combination, an adapter having a flanged collar for securing said adapter to said container, said collar having an opening therein through which the outlet end of said valve-controlling extrusion-nipple will protrude when said adapter is secured to said container, an actuator, said actuator having a through passage formed therein sized to detachably couple with a tight fit to the protruding end of said extrusion nipple, said actuator being rockably supported upon said adapter so that when said flanged collar is secured to said container the protruding end of said extrusion-nipple will engage in said through passage and couple said valve-controlling extrusion-nipple to said actuator, a duct connecting at one end to said through passage and terminating at its opposite end in an extrusion orifice, said extrusion orifice being positioned adjacent said actuator support to direct extrusions therefrom upon an object which rockably engages said actuator, and said actuator, when thus rockably engaged by an object, rocking relative to said adapter to cause said valve-controlling extrusion-nipple, when coupled to said actuator, to open said valve and thus dispense paste from said container, through said extrusion-nipple, said through passage, said duct, and said extrusion orifice, upon said object.

2. In a device for semi-automatically dispensing a pressurized paste-like composition and in combination, a cylindrical container for housing a paste-like composition under pressure, said container having two end walls, one of said end walls forming the closed bottom-end of said container, and the other having a throated-neck formed therein which defines the opposite end of said container, a piston chamber, seated in, and sealing, said throat, said piston chamber extending into said container and terminating in a nipple, said nipple having a central opening therein, a tube connected to said nipple and opening at its opposite end into said container, said tube being offset to lie along the cylindrical wall of said container and terminating at its open end in spaced proximity to said bottom end at its junction with said

cylindrical wall, a piston slide valve mounted to slide into said piston chamber, said piston including a nipple having ported openings therein, said nipple extending through said throat and projecting outwardly beyond said neck, said ported openings being confined within said container, an elastic washer mounted on said nipple within said throated-neck and clamped between said piston chamber and the inner face of the wall of the neck, said washer when so mounted and clamped normally enclosing said ported openings, a spring follower positioned within said piston chamber and engaging said piston to normally retain said nipple and said washer in port-sealing relation, an adapter for said container, said adapter having an annular collar adapted to fit upon the neck of said container with a press-fit, an actuator hingedly connected to said adapter, said actuator having a duct formed therein forming a female coupling for said piston slide valve nipple when the collar of said adapter is press-fitted upon said neck, the opposite end of said duct terminating in an orifice through which the paste-like composition housed in said container is dispensed whenever said piston slide valve slides into said piston chamber to uncover the ported openings in the nipple of said piston slide valve, said actuator when operatively engaged by an external object being rockable upon its hinge connection to effect said sliding movement of said piston slide valve into said piston chamber to uncover said ported openings, and said actuator and said dispensing orifice being so inter-related that when an external object is brought into operative engagement with said actuator it is simultaneously brought into position to receive the paste extruded through said dispensing orifice.

3. In a container-agitating device and in combination a wall plate having a central opening formed in the front wall thereof, said wall plate also having a shallow elongated recess formed in the rear wall thereof, said recess merging with said central opening to form a through opening with recesses radiating therefrom defining a stepped opening, a winged face plate seated in said stepped opening, said face plate having a shouldered stud integral therewith and projecting outwardly from said face plate, said stud having a free outer end which is threaded to receive a lock nut, a flanged, hollow-stemmed bracket, said flange having a central opening formed therein to pass over said shouldered stud and bring said flange and said face plate into rotatable abutment to rotate said hollow-stemmed bracket upon said stud, spring clamps spacedly fastened to said bracket for clamping a container thereto, a cavity in said face plate, a rearwardly projecting lug formed on said flange and sized to engage in said cavity, a coiled spring slidably mounted upon said stud and seated against said face plate, a washer mounted upon the free end of said stud and abutting the end of said coiled spring, a lock nut threaded upon the free end of said stud engaging said washer to apply variable tension to said coiled spring, said hollow-stemmed bracket being slidable along said stud against increased tension of said coiled spring to disengage said lug from said cavity, and said bracket being rotatable about said stud to agitate a container clamped between said spring clamps until said lug re-engages in said cavity under tension of said coiled spring to arrest rotation of said bracket.

4. In a dispensing device for detachable attachment over the neck of a pressurized, valve-controlled container which dispenses paste through a valve-controlling flexible extrusion-nipple and in combination, an adapter having a flanged collar for detachably attaching said adapter over

the neck of said container, said collar having a central opening therein through which the outlet end of said valve-controlling extrusion-nipple will protrude when said adapter is attached over the neck of said container, said adapter having a fenestrated bottom wall which is bevelled to define spaced tongues, an actuator having a through passage formed therein sized to slidably receive and to couple with a tight fit to the protruding end of said extrusion nipple, said actuator having a bottom wall which is reversely fenestrated and reversely bevelled relative to the fenestrations and the spaced tongues of said adapter, the bottom walls of said adapter and of said actuator in conjunction defining an interfitting freely attachable and detachable connection whereon said actuator is rockably supported upon said adapter so that when said flanged collar is secured over the neck of said container the protruding end of said extrusion-nipple will engage in said through passage and couple said valve-controlling extrusion-nipple to said actuator, a duct formed in the bottom wall of said actuator, said duct connecting at one end with said through passage and terminating at its opposite end in an extrusion orifice, said extrusion orifice being positioned adjacent said actuator support to direct extrusions therefrom upon an object which rockably engages said actuator, and said actuator, when thus rockably engaged by an object, rocking relative to said adapter to cause said valve-controlling extrusion-nipple, when coupled to said actuator, to open said valve and thus dispense paste from said container, through said extrusion nipple, said through passage, said duct, and said extrusion orifice, upon said object.

5. In a dispensing device for attachment over the neck of a pressurized, valve-controlled container which dispenses paste through a valve-controlling extrusion-nipple and in combination, an adapter having a flanged collar for securing said adapter over the neck of said container, said collar having an opening therein through which the outlet end of said valve-controlling extrusion-nipple will protrude when said adapter is secured over the neck of said container, an actuator, said actuator being rockably supported upon said adapter so that when said flanged collar is secured over the neck of said container said extrusion-nipple will enter said actuator, said actuator having a throated passage formed therein terminating in a restricted extrusion orifice which is normally overlapped by said adapter, said throated passage being sized to enclose said extrusion nipple with a tight fit thus detachably coupling said extrusion-nipple to said actuator to provide a paste-dispensing passage extending from the control valve through said extrusion-nipple and said throated passage to said normally-overlapped extrusion orifice, so that when an object rockably engages said actuator the movement of said actuator exposes said extrusion orifice and operates said extrusion nipple to open the control valve and establish a paste-dispensing passage extending from said container to said extrusion orifice, and said extrusion orifice being so positioned relative to said actuator and its support that paste dispensed through said extrusion orifice is deposited upon said actuator-rocking object.
